UNITED STATES PATENT OFFICE.

JAMES MICHAEL HINES, OF ALBANY, NEW YORK.

SLACK-ADJUSTER FOR BRAKES.

No. 848,993.

Specification of Letters Patent.

Patented April 2, 1907.

Application filed August 2, 1906. Serial No. 328,845.

To all whom it may concern:

Be it known that I, JAMES MICHAEL HINES, residing and having a post-office address at No. 3 Martin avenue, city of Albany, State 5 of New York, have invented certain new and useful Improvements in Slack-Adjusters for Brakes; and I do hereby declare the following to be a full, clear, and exact description of the invention, such as will enable others 10 skilled in the art to which it appertains to make and use the same.

My invention relates to slack-adjusters for car-brakes, and is intended to supply improved means for taking up the slack due to 15 the wear of the brake-shoes and wheels and the stretching and bending of the brake-operating levers and rods.

In carrying out my invention I provide an independent retainer connected to each 20 brake-beam by a lost-motion device and adapted to be set by the brake-applying movement to limit the withdrawal of the brake-shoes on the releasing movement to the range of movement of the lost-motion 25 device. This limitation of the withdrawal of the brake-shoes would ordinarily prevent the return of the live lever (and the piston of the air-brake cylinder when air-brakes are employed) to its original position. To avoid this, 30 I provide mechanism to take up the slack in the system of brake-applying levers and rods on the releasing movement of the brakes and to thus allow the return of the live lever to its normal position, the slack-take-up mechanism being provided with means for holding 35 the slack taken up.

My improvements will be understood from the following specification and drawings, which describe and illustrate a structure, 40 which embodies the preferred form of my invention as applied to a four-wheel truck.

In the drawings, Figure 1 is a plan view of a four-wheeled truck equipped with brake mechanism embodying a preferred form of 45 my improvements. Fig. 2 is a side elevation on line 2 of Fig. 1. Fig. 3 is a detail view of the retainer-ratchet mechanism. Fig. 4 is a detail view of the slack-take-up ratchet mechanism. Fig. 5 is a cross-section on line 50 5 of Fig. 4.

Referring to Figs. 1 and 2, A is the rod which extends to the piston of the brake-cylinder (not shown) and which is connected to and actuates the live lever B, pivoted in a strut C, extending from the brake-beam D to the truss E. This live lever B ex-

tends downwardly and transversely, as illustrated, and has connected to its lower end the rod F, which is connected to the lower end of the dead lever G. The dead lever G 60 is supported in substantially the same manner as the live lever B. The brake-shoes a are secured to the brake-beam D and hung from the end bar of the truck in any appropriate manner, and springs b serve to draw 65 the brake-shoes away from the wheels when the brakes are released.

The retaining mechanism and lost-motion connection is constructed in the following manner: Projecting upwardly from the strut C is a short forked arm c, in the fork of which the connecting-rod d is pivoted. The other end of the rod d is provided with a slot which plays on a pin in the forked lower end of the lever e, which lever is pivoted in a bracket f, 75 secured to the cross-bar H. Pivoted to the upper end of the lever e is a connecting-rod g, which is secured at its other end to the box h, sliding on the rack-bar i and carrying retaining-pawl k, adapted to interlock with the 80 teeth on the rack-bar i. The dead lever G is pivoted in the strut C', extending from the brake-beam D' to the truss E'. This strut C' is provided with a forked arm c', connected to the rod d', the lever e', the connecting-rod 85 g', and the ratchet-box h', all of these parts and supports being similar to corresponding parts at the other end of the truck. Pivoted to the upper end of the lever G is a connecting-rod m, which is attached to the box n, 90 sliding on the rack-bar o and carrying the pawl p, adapted to interlock with the teeth on the rack-bar. The pawl k is provided with a pin r, so that when it is desired to release the slack which has been taken up for 95 the application of new shoes, &c., the pawl k may be turned on its pivot out of engagement with the rack-bar and retained in this inoperative position by swinging the hook s over the pin r. A similar arrangement is 100 provided for the box h'. To the pawl p is fastened an arm t, to which the rod u is connected, and this rod u has a bent portion at its other end, adapted to be placed in the slot in the connecting-rod m, as shown in 105 Fig. 1. The purpose of this rod u is to allow the attendant to turn the pawl p on its pivot, thus disengaging it from the rack o and rendering it possible to move the box n to the right to release the slack which has been 110 taken up when it is desired to apply new shoes, &c.

The operation of the parts is as follows: If power is applied to the brake-cylinder, the movement of the piston will pull on the rod A and move the brake-beam and brakes toward the wheels. If the length of the slot in the connecting-rod d is less than the distance through which it is necessary to move the brakes in order to bring them into contact with the wheels, the end of the slot in the rod d comes into contact with the pin on the lever e and turns that lever on its pivot, thus moving the connecting-rod g and the box h to the left, the pawl k riding on the rack i. At the same time a similar action has taken place in connection with the other brake-beam through the rod d', the lever e', the rod g', and the box h'. When the brakes are released, the pawls in the boxes h and h' engage with their respective racks, preventing the return of the levers e and e' to their original positions, and thus limiting the movement of the brake-beams and shoes away from the wheels and retaining that portion of the movement of the brake beams and shoes which is due to the slack in the mechanism. On the return movement of the brake-piston the live lever B moves with the strut C until the right-hand end of the slot in the connecting-rod d engages with the pin on the lever e. This movement is sufficient to release the brakes. The further movement of the brake-piston in returning to its original position turns the live lever on its pivot and through the connecting-rod F turns the dead lever G and through the connecting-rod m causes the box n to slide to the left over the rack o. At the end of this movement the pawl p engages with the rack o and prevents the return of the dead lever, thus taking up the slack in the brake mechanism and establishing a new fulcrum for the system of levers. Thereafter upon each release the brake-shoes fall back only the distance allowed by the slots in the rods d and d', and upon any application of the brakes the movement is through only the distance allowed by these slots until the wear of brake-shoes or wheels or the bending of the levers and rods has created sufficient slack to permit the movement of the box n another notch to establish a new fulcrum for the system.

It will be understood that though I have described in detail the preferred form of my invention in order that those skilled in the art may be able to construct the same, yet my invention is not limited to the specific details so described.

Having thus described my invention, what I claim is—

1. In a brake mechanism for vehicles, brake-beams, brake-shoes carried thereby, brake-applying mechanism for moving said beams and shoes toward the wheels to apply the brakes, a separate mechanism associated with each brake-beam and independent of

the brake-applying mechanism for retaining that portion of the brake-applying movement which is due to the slack in the brake mechanism, and means for automatically adjusting the brake-applying mechanism to take up the slack on the releasing movement of the brakes. 70

2. In a brake mechanism for vehicles, brake-beams, brake-shoes carried thereby, means for moving said beams toward the wheels to apply the brakes, a retainer attached to each brake-beam actuated by the brake-applying movement thereof to limit the movement of the brake-beam away from the wheels, and means for automatically adjusting the brake-applying mechanism to take up the slack therein on the releasing movement of the brakes. 75 80

3. In a brake mechanism for vehicles, a system of levers, brake-beams adapted to be actuated by said levers, brake-shoes carried by said beams, a retainer connected to each brake-beam by a lost-motion device and adapted to be set by the brake-applying movement to limit the withdrawal of the brake-shoes, and means for taking up the slack in the system of levers on the brake-releasing movement. 85 90

4. In a brake mechanism, a plurality of brake-beams, brake-shoes carried thereby, a live lever mounted on a single free pivot fixed with relation to one of said brake-beams, a dead lever mounted on a pivot fixed with relation to another of said brake-beams, means for creating a fulcrum for said dead lever 100 fixed with relation to the vehicle or truck-body, means independent of said levers for limiting the movement of the brake-beams away from the wheels, and means for automatically adjusting the position of the fulcrum for the dead lever on the releasing movement of the brakes. 105

5. In a brake mechanism for vehicles, two brake-beams, brake-shoes carried thereby, a live lever mounted on a pivot fixed with relation to one brake-beam, a dead lever mounted on a pivot fixed with relation to the other brake-beam, means for applying the braking power to one end of the live lever, a connection between the live lever and the dead lever, adjustable mechanism connected to each of the brake-beams and adapted to limit the movement thereof away from the wheels, means for creating a fulcrum for the dead lever fixed with relation to the truck-frame, 115 120 and means for adjusting the position of said fulcrum on the releasing movement of the brake mechanism. 125

6. In a brake mechanism for vehicles, two brake-beams, brake-shoes supported thereby, a live lever mounted on a pivot fixed with relation to one brake-beam and a dead lever mounted on a pivot fixed with relation to the other brake-beam, means for applying the braking power to the live lever, connections 130

between the live lever and the 'dead lever,' a retaining-lever mounted adjacent to each brake-beam and connected thereto by a lost-motion device, a rack adjacent to each of 5 said retaining-levers, pawls adapted to engage with the said racks, connections between the retaining-levers and said pawls, a rack mounted adjacent to the dead lever and a pawl connected to the dead lever adapted 10 to engage with the said rack; substantially as and for the purpose described.

7. In a braking mechanism for vehicles, a plurality of brake-beams, brake-shoes supported thereby, brake-applying levers mounted on pivots fixed with relation to said beams, 15 means for applying the braking power to one of said levers, connections between said le-

vers, a pivoted retaining-lever mounted adjacent to each brake-beam and connected thereto by a lost-motion device, a rack adjacent to each of said retaining-levers, pawl-boxes mounted on said racks, connections between the pawl-boxes and the retaining-levers, a rack adjacent to one of the brake-applying levers, a pawl-box sliding on said rack, 20 and connections between the said pawl-box and adjacent lever, substantially as described.

In testimony whereof I affix my signature in presence of two witnesses.

JAMES MICHAEL HINES.
